UNITED STATES PATENT OFFICE.

VICTOR L. J. BOURGEOIS, OF MONTREAL, QUEBEC, CANADA, ASSIGNOR OF ONE-HALF
TO JOSEPH NAZAIRE DUBOIS, OF MONTREAL, CANADA.

LOADING AND UNLOADING APPARATUS FOR VEHICLES.

1,391,607.

Specification of Letters Patent. Patented Sept. 20, 1921.

Application filed November 29, 1919. Serial No. 341,456.

To all whom it may concern:

Be it known that I, VICTOR L. J. BOURGEOIS, a subject of the King of Belgium, residing at Montreal, Province of Quebec, 5 Canada, have invented certain new and useful Improvements in Loading and Unloading Apparatus for Vehicles; and I do hereby declare that the following is a full, clear, and exact description of the invention, such 10 as will enable others skilled in the art to which it appertains to make and use the same.

The present invention has relation to loading and unloading apparatus for vehicles 15 or the like and the principal object resides in the provision of means for the simple and expeditious elevation or lowering of the materials to and from the vehicle bed or the like.

20 Another object of the invention is to provide mechanism arranged for connection to the vehicle frame and adapted for actuating the platform of the apparatus and which may be operated, manually or by a draft 25 animal, or actuated in connection with the driving engine, when motor trucks are used.

A further object is to provide an elevating platform adapted for attachment to the vehicle frame to form the body of the vehicle.

30 A still further object is to provide an elevating platform adapted with its guide element, to be detached from the vehicle and disposed out of the way upon the same.

35 With the above and other objects in view which will hereinafter appear as the description continues, the invention consists of the novel features of construction, combination and formation of parts as will be herein- 40 after more fully described and particularly pointed out in the appended claims.

In the accompanying drawings has been shown a simple and preferred form of the invention, it being, however, understood that 45 no limitation is necessarily made to the precise structural details herein exhibited, but the right is hereby reserved to any changes, alterations or modifications to which recourse may be had that come within the 50 scope of the claims without departing from the spirit of the invention or sacrificing the efficiency of the same.

The invention has been illustrated in its

preferred and modified embodiments in the accompanying drawings, wherein:

55

Figure 1 is an elevational view of a wagon, illustrating the application of the preferred embodiment of the invention thereto;

60

Fig. 2 is a longitudinal section of the same with portions broken away;

Fig. 3 is a magnified sectional elevation of the platform and guide frame;

Fig. 4 is a plan view of the vehicle bed, platform and guide frame;

Fig. 5 is a partial longitudinal sectional view, with the elevating platform disposed under the vehicle frame;

65

Fig. 6 is a cross section illustrating the operative mechanism of the platform, with the latter portioned with the vehicle and the guide frame stowed away;

Fig. 7 is a bottom plan elevation of the same;

Fig. 8 is a detail sectional elevation, illustrating the disposal of the guide frame when not in use;

75

Fig. 9 is a fragmental longitudinal section of the vehicle bed and platform, with the guide frame in elevation;

Fig. 10 is a longitudinal section of a modified form of the platform and guide frame;

80

Fig. 11 is a plan elevation of the same;

Fig. 12 is an edge elevation of the modified form of guide frame, when the same is collapsed;

85

Fig. 13 is a further modified form of platform and guide frame;

Fig. 14 is a detail elevation and section of the platform and frame of the same; and,

Fig. 15 is a plan view of a portion of the operative mechanism of the platform.

In carrying out the present invention, reference being had to the drawings in detail, there is provided a wheel supported vehicle body 10, having a flooring 11. Secured to the vehicle floor 11 and extending longitudinally thereof, are a pair of rails 12, which are disposed adjacent and extend in alignment with the said walls 14 of the body.

The rear end of the vehicle floor 11 has secured thereto, by means of the straps 15 a cross rod 16.

A guide frame 17 comprising bars 18 and 19 are pivotally connected together intermediate their ends by the cross bars 20, while their upper and lower ends are connected by

bars 21 and 22 respectively, the latter forming the base of the said frame 17. As bars 18, 19, 20 and 21 are pivotally connected by the pins 23, the said frame may be collapsed 5 when not in use. Bars 18 are formed with upwardly opening confronting channels 24 and at their upper ends are provided with hooks 25 adapted for engagement with the cross rod 16, whereby the same is attached 10 to the wagon bed. When the guide frame 17 is attached to the said cross rod 16, the bars 18 and 19 are disposed at an angle with respect to the base bars 22 and top cross bars 21 and the latter are so positioned that 15 their vertical edge portions extend in alignment with the rails 12 of the vehicle body 10.

A platform 26 is adapted for adjustment upon said guide frame 17, having secured to its opposite ends the bearing plates 27 in 20 which are located the shafts 28 carrying the grooved rollers 29 and 30. The rollers 30 are operable within the channeled portion 24 of bars 18, while rollers 29 have bearings at 25 their grooved portions upon the outer edge of bars 19. As will be understood, platform 26 is adapted for movement upon the guide frame 17, for elevating loads to the floor 11 of the vehicle and upon reaching the top of the bars 18 and 19 the rollers 30 will run 30 upon the rails 12, while the rear rollers 29 will run upon the outer edges of top bars 21, arranged in alignment with the rails 12.

The elevating platform 26 is actuated in the following manner:

35 A shaft 31 extends transversely of and is secured, to the under surface of the wagon floor 10 at its medial part, by the bearing standards 32 and said shaft 31 adjacent each end has secured thereto the drums 33 and 34 around which are trained the cables 35 and 36. The cables pass over pulleys 47 in the wagon floor 11 and the opposite ends of said cables 35 and 36 are secured by bolts 37 to the low side walls 38 of the movable platform 26. One or both ends of shaft 31, may project from beyond the sides of the vehicle and carry a gear 39, which is in meshing engagement with a smaller gear 40, mounted on a pin shaft 41. A strap member 42 secured at its ends to the depending frame bar 43, is provided with openings through which project the ends of shaft 31 and 41, which latter are squared at 44, and adapted for seating within the opening in the crank handle 45, by means of which shaft 31 is revolved to wind up cables 35 and 36 upon drums 33 and 34 to elevate said platform 26 to the wagon bed 11. Likewise pin shaft 41 has keyed thereon a toothed ratchet member 46, adapted for engagement with a pawl 47 pivotally mounted at one end in the frame bar 43. The function of the pawl and ratchet mechanism is to prevent the back rotation of shaft 31, while the same is being actuated to elevate the platform 26.

It will be readily seen that upon the rotation of shaft 31, through its associated gear elements and drums, that cables 35 and 36 will be wound upon drums 33 and 34, resulting thereby in the elevation of platform 26 upon the guide frame 17 and into the vehicle proper, by the engagement of the pulleys or wheels 29 upon the rails 12 of the vehicle bed. In this manner, the loads are assembled upon the platform 26, which latter is always maintained in horizontal position with respect to the guide frame 17. Pulleys or wheels 29 and 30 will engage bars 18 and 19 respectively and upon maximum elevation of said platform the wheels will rest on the rails 12 of the body and cross bars 21. As the rails 12 and the cross bar edges are in alignment, the platform 26 attached to the cables 35 and 36, will be drawn unto the vehicle bed 11, the said cables passing over the oppositely disposed pulleys 46 on the cross rod 16. When the platform 26 is elevated to the vehicle bed the forward rollers 30 will engage or travel upon the horizontal portions 47 of rails 12, while the rollers 29 will engage the vertical web portions 48 thereof.

The platform 26, when not in use, may be stowed out of the way beneath the vehicle frame, within an opening casing 49, as illustrated in Fig. 5, and a spring 50 secured to the top wall of casing 49 serves with a spring catch 51, to hold the said platform within the casing 49.

Guide frame 17 may be collapsed and the sections lowered within the brackets 52 and 53 at the ends of the vehicle body 10.

In the modified form illustrated in Figs. 10 to 12 inclusive, the numeral 54 designates the vehicle bed, the same being constructed in the form of a metallic frame, provided with L-shaped rails 55 and a cross rod 56 secured by straps 57 to the side walls of the vehicle body. This rod 56 likewise carries a pair of pulleys 58 over which are trained cables 59, secured to the forward end of the movable platform 60.

A guide frame 61 is adapted for detachable connection to the rear open end of the vehicle frame and comprises upright bars 62, 63, and 64, a base bar 65 of substantially L-configuration, and the connecting bars 66 and 67. Bar 62 is likewise of L-configuration and is connected to rail bars 66 and base bars 65 by the pivot pins 68, while upright bars 63 and 64 are connected to the bars 66, 67 and the base bars 65 by pivot pins 69. Likewise bars 62 at their upper ends are formed with hook members 70, adapted for engagement with rod 56 of the vehicle frame for holding the said guide frame 61 thereon.

Platform 60 comprises an elongated rectangular metallic body having secured to its lower surface the bearing brackets 71 in which are mounted the shafts 72, 73, and 74.

74. Shaft 72 carries the plain rollers 75, while shaft 73 carries the grooved rollers 76 and the shaft 74 carries the double grooved rollers 76.

5 Secured to each side of the rail bars 66 and 67 are the pivotally connected outer rail bars 77 and 78. The outer grooved portion of rollers 76 ride upon the edge of outer rail bars 77 and 78, while the rollers 76 ride upon the bars 63, and rollers 75 travel upon the L-bars 62. Upon reaching the top of the guide frame the platform rollers will travel upon the rails 66 and 55 and be moved inwardly unto the vehicle frame. This form 10 of guide frame may be collapsed and in an appropriate manner stowed away in the vehicle frame.

In the modification illustrated in Fig. 13 the guide frame comprises the longitudinal bars 79, 80 and 81, the top and intermediate bars 82 and 83 and the base bars 84, and all 20 of said bars are connected together by pivot pins 85, so that the said guide frame may be collapsed when not in use. Bars 79 are 25 of L-configuration in cross section while base bars 84 are provided with channels 86.

The base bars 84 have secured to their outer ends the plates 86 upon which ride the rollers 87, 88 and 89 of platform 90, when 30 the latter is to be elevated upon said guide frame. Rollers 86 when the platform is to be elevated will pass through the channels 86 of the base plates 84 and upwardly upon the horizontal surface of bars 79. Rollers 35 88 will engage within the channels 86 of the base rod and the outer edges of bars 80, while rollers 89 will ride upon the outer edges of the bars 81. Upon the elevation of the platform 90 to the top of the guide frame the 40 rollers 87, 88 and 89 will ride upon the top edges of bars 82, which latter are in alignment with the rails 91 of the vehicle body. Hooks 92 are formed on the bars 79 and are 45 adapted to be secured to the cross rod 93 of the vehicle frame. Likewise the guide frame may be collapsed and stowed away within the vehicle frame.

Manually operable means for elevating the lifting platform may be dispensed with and 50 the hoisting mechanism may be directly connected to the shaft of an explosive-engine, more particularly used in the propulsion of motor trucks and thus the load may be elevated without resorting to the crank handle 55 for the actuation of the mechanism illustrated in Fig. 6.

It is obvious that by the construction and use of an apparatus of the character described, very heavy loads may be elevated 60 or lowered from the ground to the vehicle, thus doing away with the labor usually employed in this connection.

The platforms may be loaded at the proper place and hauled to the guide frames and 65 elevated unto the vehicle.

Likewise the construction may be applied to railway baggage or freight conveying trucks in which the operative mechanism may be connected to the propulsion motor to elevate a platform to the level of the car 70 door.

By this construction, it is obvious that a liquid load may be elevated or lowered from a vehicle, as the platform will always be disposed in horizontal plane, and likewise the 75 same means may be employed to elevate furniture, safes or the like, to different floors, by providing a frame of the required length. Likewise the apparatus may be employed with great advantage for loading freight 80 cars.

Having thus fully described my invention, what I claim as new and desire to secure by Letters Patent is:—

1. The combination with a vehicle, a frame 85 including spaced side members attached to the rear end of said vehicle, said frame comprising a plurality of hinged sections, inclined tracks attached to the side members of the frame, and a carriage mounted on the 90 tracks to ride upwardly thereon and upon the side members of the frame into said vehicle.

2. The combination with a vehicle, including a horizontally disposed bottom, a frame 95 extending rearwardly therefrom, having its upper edge flush with the upper side of the vehicle bottom, said frame including spaced side members and comprising a plurality of hinged sections, inclined tracks pivotally 100 connected to the side members, for collapsible movement relative thereto, and a carriage mounted on the inclined tracks for upward movement thereon, in a horizontal plane, said carriage being movable on the 105 tracks and on the side members of the frame, and into the body of the vehicle, substantially as and for the purposes set forth.

3. The combination with a vehicle, including a body having a horizontally disposed 110 bottom, said bottom having grooves therein, a frame attached to the rear end of the bottom of the vehicle body, said frame including spaced side members, inclined tracks pivotally connected to the side members for folding movement relative thereto, a car mounted upon the inclined tracks and movable upwardly and downwardly thereon, said car being disposed in the same plane 115 as the bottom of the vehicle body, and movable along the side members of the frame, cables mounted in the grooves of the vehicle body and attached to the car, for actuating the same, and means for winding and unwinding the cables, substantially as and 120 for the purposes set forth.

In witness whereof I have hereunto set my hand.

VICTOR L. J. BOURGEOIS,
